UNITED STATES PATENT OFFICE.

JACOB BINNIG, OF BOSTON, MASSACHUSETTS, ASSIGNOR OF ONE-HALF TO
MASON & HAMLIN COMPANY, OF CAMBRIDGE, MASSACHUSETTS, A COR-
PORATION OF DELAWARE.

ORGAN KEY-ACTION.

No. 850,413.

Specification of Letters Patent.

Patented April 16, 1907.

Application filed March 10, 1906. Serial No. 305,209.

To all whom it may concern:

Be it known that I, JACOB BINNIG, a citizen of the United States, and a resident of Boston, in the county of Suffolk and State of Massachusetts, have invented an Improvement in Organ Key-Actions, of which the following description, in connection with the accompanying drawings, is a specification, like letters on the drawings representing like parts.

This invention has for its object to provide a novel key-action for an organ which is so constructed as to render the operation thereof very delicate. This result is secured by providing means whereby the valve controlling the supply from the wind-chest will close, thereby causing the pipe to cease speaking as soon as the pressure on the key is relieved and during the first part of the upward movement of the outer end thereof.

In all organ-actions with which I am familiar the construction is such that a pipe will not cease speaking until the key has nearly resumed its initial position, and the result of this construction is that it is not possible to make the same pipe speak rapidly at extremely short intervals of time without having the separate sounds run together. This is overcome with my invention because as soon as the key is released and before the outer end completes its upward movement the pipe will cease speaking, and the key may be rapidly operated, therefore, to cause a plurality of rapid staccato notes without any blending of the successive notes.

I have herein shown my invention as embodied in a mechanical key-action—that is, one in which the key is connected to the valve by a mechanical connection which is adapted to transmit the motion of the key to the valve—and in applying my invention to this type of key-action the mechanical connection between the key and valve is provided with a lost-motion device, which preferably is a frictional device, the friction of which is sufficient to cause the valve to move with the key during the first part of the movement thereof from the abnormal or playing position of the key (that is, the position of the key when the outer end is depressed) to the normal position, (that is, the position of the key when the outer end is elevated,) said friction device permitting the key to move

relative to the valve after the latter has been shifted and during the final movement of the key. In the preferred embodiment of my invention this friction device is so constructed that the valve will move with the key during the first part of the movement thereof in either direction, said friction device permitting the key to move relative to the valve after the latter has been shifted and during the final movement of the key in either direction.

I will first describe one embodiment of my invention and then point out the novel features thereof in the appended claims.

In the drawings, Figure 1 is a side view of a key-action embodying my invention. Fig. 2 is a section on the line x, Fig. 1; and Fig. 3 is a view showing the key fully depressed.

In the drawings, 3 designates the key of an organ; 4, the wind-chest; 5, the duct leading to the primary or other pneumatic for operating the pipe-valve, and 6 and 7 the two valves which control the communication between the wind-chest and the duct 5. These parts may have any suitable or usual construction and form no part of my present invention. As herein shown, the valves 6 and 7 are mounted on a valve-stem 8, and the valve 6 is adapted to close a port 9, leading into the wind-chest 4, and the valve 7 to close a port 10, leading to the atmosphere.

When the key is in its normal position, the valve 9 is closed; but when the key is depressed or moved into its playing position for sounding a note said valve is opened and the valve 7 closed, thereby opening communication between the wind-chest and the pneumatic. It is obvious that the note will not be sounded until the valve 9 is opened and the valve 7 closed, and in order to make the key-action a delicate one and one which can be rapidly operated I have provided means whereby the valve controlling the supply of wind from the wind-chest will be closed during the first part of the upward movement of the key—that is, the movement from the playing position to the normal or initial position—the valve being completely closed before the key has reached its normal or initial position. The means above described are also preferably so constructed that said valve will be opened during the first part of the downward movement of the key and before

- the key has been depressed to its lowest position. The means I have herein illustrated for accomplishing this object comprises two frictionally-connected members, through 5 which movement is transmitted to the valve. These two members are so connected that they move together during the first part of the movement of the key, and the friction between them is sufficient to shift the valve.
- 10 The key has a movement greater than is necessary to completely shift the valve, and after the valve has been fully shifted during the first part of the movement of the key the remainder of the movement of the key is permitted by the slipping of the two frictionally-connected members on each other.
- 15 In the embodiment of the invention herein illustrated one of the frictionally-connected members is the stem 8 of the valve, and the
- 20 other of the frictionally-connected members may either be the key 3 or an actuator, the latter arrangement being shown in the drawings. The actuator is designated by 12, and it is pivoted at one end to a fixed support, as
- 25 at 13, and at the other end carries an adjustable button 14 to be engaged by the inner end of the key 3. A spring 15, acting on the upper side of the actuator, tends to return the key to its normal position and to close
- 30 the valve 6. The necessary frictional connection between the valve-actuator and the valve-stem is in this embodiment provided for by providing the actuator with a recess 16, one side of which is covered by a frictional pad 17, 35 against which the valve-stem 8 rests. Said valve-stem is frictionally held against this friction-pad by means of a yieldingly-mounted frictional pad 19, which is shown as received in the recess 16 and as being yieldingly held
- 40 against the valve-stem 8 by means of a spring or other resilient member 20. The said valve-stem is provided with two adjustable buttons 21 and 22, which serve to keep the valve-stem properly positioned with reference to the actuator. The friction between the valve-stem and the actuator is sufficient to cause the valves to be shifted by the initial movement of the actuator, while allowing the actuator to move relatively to the valve- 45 stem after the valves have been shifted.
- 50 The operation of the device will be apparent from the foregoing. The parts are shown in full lines in Fig. 1 in their normal position. When the key 3 is depressed for sounding a note or moved into its playing position, the inner end thereof is elevated, thereby lifting the valve-actuator 12. Owing to the frictional engagement between the valve-stem and said actuator, the initial movement of the 55 actuator shifts the valves, thereby setting in operation the pneumatics which sound the note, and this shifting of the valves will occur during the first part of the downward movement of the outer end of the key, or its
- 60 movement from the full to the dotted line

position, Fig. 1. It requires, however, a comparatively slight movement of the key to completely shift the valves, and as the key is further depressed the actuator will slide on the valve-stem and assume the position 70 shown in Fig. 2. As soon as the key is released the initial movement of the actuator will owing to its frictional connection with the valve-stem shift the valves to close the port 9, and during the further movement of 75 the key and actuator into the full-line position, Fig. 1, said actuator will slide down on the valve-stem. It will thus be seen that the valves are always shifted in one direction or the other during the first part of the movement of the key in either direction, and the result is that the note will be sounded as soon as the key is touched, and the sound will cease as soon as the key is released.

The drawings show one embodiment of my 85 invention, and as the desired connection between the valve-stem and key 3 may be provided for in various ways I do not wish my claims to be limited to the particular construction herein shown.

Having described my invention, what I claim as new, and desire to secure by Letters Patent, is—

1. In a key-action, a key, a valve, and devices including two frictionally-connected 95 members for transmitting the movement of the key to the valve.
2. In a key-action, a key, a valve, and devices including two frictionally-connected members for transmitting the movement of 100 the key to the valve, said key having a greater movement than is necessary to operate the valve.
3. In a key-action, a key, a valve, and means to open the valve during the first part 105 of the movement of the key in one direction, and to close the valve during the first part of the movement of the key in the opposite direction.
4. In a device of the class described, in 110 combination, a wind-chest, a valve therefor, and a spring-pressed pivotally-mounted member for actuating the valve frictionally connected thereto.
5. In a key-action in combination, a wind- 115 chest, a valve therefor, a spring-pressed valve-actuator frictionally connected to the valve, and a key for operating the actuator in one direction.
6. In a key-action in combination, a wind- 120 chest, a valve therefor having a valve-stem, a pivotally-mounted spring-pressed valve-actuator frictionally connected to the valve-stem, and a key for moving the actuator in one direction.
7. In a key-action, a key, a valve operated thereby, said key having a greater movement than necessary to operate the valve, and means whereby the valve is completely 125 shifted during the first part of the movement 130

of the key in either direction and before said key completes its movement.

8. In a key-action, a key, a valve-actuator operated thereby, a valve, and connections, including a friction device, between the valve-actuator and the valve, said friction device operating to shift the valve upon the first part of the movement of the actuator and allowing said actuator to move relative

10 to the valve after the valve has been shifted.

9. In a key-action, a valve having a valve-stem 8 and a valve-actuator 12 frictionally connected to the valve-stem and a key for moving the actuator.

15 10. In a key-action, a valve having a valve-stem 8, a valve-actuator 12 frictionally connected to the valve-stem, said actuator hav-

ing a greater range of movement than the valve, and a key for moving the valve-actuator in one direction.

11. In a key-action, in combination, a wind-chest 4, a valve to control the supply of wind therefrom, said valve having a stem 8, and a pivoted device having a frictional engagement with said stem for actuating the 25 valve.

In testimony whereof I have signed my name to this specification in the presence of two subscribing witnesses.

JACOB BINNIG.
